COSMETIC APPLICATOR

Charles A. Mureau, Los Angeles, Calif.

Application February 15, 1937, Serial No. 125,798

18 Claims. (Cl. 132—79)

This invention relates to a device for applying cosmetics, etc., and relates more particularly to a device for containing and applying mascara and the like. It is a general object of this invention 5 to provide a practical, compact device for carrying mascara and the like and for facilitating the use or application of the same.

Mascara is marketed in the form of a cake which must be brushed with a moist brush before 10 application by the brush and is also marketed in the form of a cream contained in a collapsible tube from which it may be expelled upon a brush for use. In using both forms of the cosmetic it is necessary to carry a supply of the mascara and 15 a loose or separate brush for applying the same. The brush after use soils the hands and clothing and must be washed from time to time to obtain the best results. As the brush is exposed to the atmosphere the mascara hardens upon it in the 20 form of hard particles that must be removed before the brush can be used. The cake or the tube containing the mascara also becomes very un- 25 sightly and soiled and is inconvenient to handle and carry about.

Another object of this invention is to provide 25 a device for applying mascara that embodies a case containing a supply of the cosmetic, a brush normally enclosed in the case and projectable for applying the cosmetic and a slide for applying or 30 wiping the mascara on the brush while the same is in the case so that the brush carries a proper amount of the mascara when projected for use.

Another object of this invention is to provide a device of the character mentioned for containing 35 and applying mascara or the like that may be handled and employed without bringing the hands in contact with the brush or the cosmetic so that the hands do not become soiled.

Another object of this invention is to provide a 40 device of the character mentioned in which the cosmetic is contained in a substantially air tight and leak proof compartment of the case so that it is preserved in the proper condition and does not leak from the case.

Another object of this invention is to provide a 45 device of the character mentioned in which the proper amount of the cosmetic is automatically withdrawn from the supply compartment and evenly distributed on the brush by merely recipro- 50 cating the slide while the brush is housed within the case.

Another object of this invention is to provide a 55 device of the character mentioned in which the cosmetic carrying portion of the slide is never

projected from the case to soil the hands or clothing.

Another object of this invention is to provide a device of the character mentioned that is long wearing and that embodies a readily replaceable 5 brush.

Another object of this invention is to provide a device of the character mentioned that is easy and convenient to use and that may be readily 10 replenished with a supply of the cosmetic.

The various objects and features of my invention will be fully understood from the following 15 detailed description of a typical preferred form and application of my invention, throughout which description reference is made to the accompanying drawing, in which:

Fig. 1 is a side elevation of the device provided by this invention showing the brush-carrying arm in the down or retracted position. Fig. 2 is an 20 end view of the device. Fig. 3 is a longitudinal detailed sectional view of the device illustrating 25 the brush and slide in side elevation. Fig. 4 is a transverse detailed sectional view taken as indicated by line 4—4 on Fig. 3. Fig. 5 is an enlarged longitudinal detailed sectional view taken as indicated by line 5—5 on Fig. 8. Fig. 6 is a transverse 30 detailed sectional view taken as indicated by line 6—6 on Fig. 3. Fig. 7 is a side elevation of the device with the slide in the extended or operative 35 position and with a portion broken away to illustrate the slide in cooperation with the brush. Fig. 8 is a reduced side elevation of the device showing the brush in the extended or operative position and Fig. 9 is an enlarged fragmentary longitudinal detailed sectional view illustrating the latch 35 for releasably holding the brush arm in the re- tracted position.

The cosmetic applying device of the present invention includes, generally, a body or case 10 having a compartment 11 for holding a supply 40 of the cosmetic, a brush 12 carried by the case 10 for movement between a position within the case and a projected position and a slide 13 for withdrawing the cosmetic from the compartment 11 and applying it to the brush 12 within the 45 case 10.

The case 10 carries or contains the various 50 elements of the device and in accordance with the invention is shaped and proportioned for convenient handling and to be carried in a pocket- book, purse or the like. In the form of the invention illustrated the case 10 is a hollow rec- tangular member comprising what I will term a lower wall 14, sides 15, ends 16 and 17 and a top 18. The lower wall 14, the sides 16 and 17, 55

and the top 18 are all rigidly joined together and their external surfaces may be suitably finished, for example, they may be plated. In accordance with the invention a partition 19 extends transversely through the case 10 to divide its interior into the supply compartment 11 and an opening or chamber 20 for receiving the brush 12. In practice the compartment 11 for containing the supply of the cosmetic may be somewhat longer than the brush chamber 20. An opening 21 is provided in the case end 16 through which the cosmetic may be passed or supplied to the compartment 11. The opening 21 is normally closed by a removable threaded plug 22. Upon the withdrawal of the plug 22 the cosmetic may be forced into the compartment 11 from a collapsible tube carrying the cosmetic in a semi-liquid or paste form.

The top 18 of the case 10 is provided with an opening 23 for receiving the brush 12. The opening 23 communicates with the upper end of the chamber 20 and its walls are inwardly convergent, as illustrated in Figs. 3, 6 and 7. The partition 19 is thickened so that its surface which forms the inner wall of the chamber 20 slopes or inclines downwardly and inwardly toward the center of the chamber. The inner surface of the end 17 is likewise inclined downwardly and inwardly. Instead of thickening the partition 19 and the end 17 to provide the inclined surfaces just mentioned suitable plates or parts may be provided on the end and partition to present the desired inclined surfaces. Plates 24 are provided on the inner surfaces of the case sides 15 to form the side walls of the chamber 20. The inner surfaces of the plates 24 slope downwardly and inwardly with respect to the center of the chamber 20. The lower ends of the plates 24 and the lower ends of the inclined surfaces on the end 17 and the partition 19 are spaced above the lower wall 14, the lower edges of the plates 24 being below the lower ends of the inclined surfaces. While I have shown the plates 24 integrally joined with the ends 17 and the partition 19 it will be understood that the sides 15 may be thickened to present the desired inclined surfaces. The chamber 20 is provided with the above described inclined walls to guide the brush 12 when it is moved into the chamber and to prevent the brush from being fouled and drawn inwardly by the slide 13 when the slide is moved inwardly into the compartment 11.

The brush 12 is provided to apply the cosmetic or mascara and is projectable from the chamber 20 to an extended position such as illustrated in Fig. 8, to be conveniently used for applying the cosmetic. The brush 12 includes a stem or arm 25. The arm 25 is hinged or pivoted to the case 10 so that the brush 12 may be swung between a position in the chamber 20 and the position shown in Fig. 8. In the particular structure illustrated an end of the arm 25 is received between spaced lugs 26 on the top 18 and a pivot pin 27 extending between the lugs 16 pivotally connects the arm 25 with the case 10. The arm 25 is preferably hinged to the top 18 at a point some distance from the end 16 so that the arm may engage against the top 18 when the brush 12 is in its fully extended position illustrated in Fig. 8 to assist in holding the brush in place for use. The above described pivotal mounting or support for the brush arm 25 may have a spring means or a friction means for yieldingly holding the arm 25 against movement when the brush 12 is in the chamber 20 and when the brush 12

is in its fully extended position. When the brush arm 25 is flat against or adjacent the top 18 its outer end may project slightly beyond the case end 17 to present a lip 28 engageable by a finger or finger-nail for raising the brush arm. A spring clip 29 may be provided on the case 10 to cooperate with a lug 29a on the arm 25 to yieldingly hold the brush arm 25 in the normal or retracted position.

A plate 30 is secured to the under side of the arm 25 to carry the brush 12 proper and to close the opening 23 when the brush is within the chamber 20. The sides and ends of the plate 30 are bevelled or inwardly convergent to seat and seal against the walls of the opening 23. When the brush 12 is in the fully retracted position the outer surface of the plate 30 may be flush with the outer surface of the top 18. The brush 12 proper includes a shank 32 and a plurality of brush tufts 33 set in the shank 32. The shank 32 may be a rectangular elongate member and is carried by the arm 25 so that the brush tufts 33 project laterally from the arm 25. It is a feature of the invention that the brush 12 is releasably secured to the arm 25 so that it may be removed for replacement when worn. The means for releasably securing the brush 12 to the arm 25 includes a groove 34 in the plate 30 receiving the brush shank 32. Screws 35 are passed through openings in the brush shank 32 and are threaded into openings 36 in the plate 30 and the arm 25 to removably retain the shank 32 in the groove 34. The brush 12 is positioned on the arm 25 to be received in the opening 23 when the arm is swung to the down or retracted position. The brush tufts 33 are located and proportioned to clear the walls of the chamber 20 when the brush is moved into the chamber. The convergent walls of the chamber 20 guide the brush tufts 33 into the chamber when the tufts become worn and frayed. When the arm 25 is in its down or retracted position the outer ends of the brush tufts 33 are spaced above the lower wall 14. It will be noted that the brush 12 proper is fully enclosed and sealed in the substantially air tight chamber 20 when the arm 25 is in its closed or down position illustrated in Figs. 1, 2, 3, 4, 6 and 7 of the drawing.

The slide 13 is an important element of the device as it constitutes means for withdrawing the cosmetic from the compartment 11 and evenly distributing the proper amount of the cosmetic on the brush 12 when the same is in the chamber 20. The slide 13 is in the nature of an elongate substantially rectangular block shiftable or slideable on the inner surface of the lower wall 14 between a position in the compartment 11 and a position in the brush chamber 20. The partition 19 terminates above the lower wall 14 leaving an opening 37 that shiftably or slidably receives the slide 13.

The slide 13 is shaped or formed to carry or withdraw cosmetic from the compartment 11 when it is moved outwardly into the brush chamber 20. A multiplicity of teeth 38 is provided on the upper or inner side of the slide 13. The teeth 38 may be similar to gear teeth or may be V-shaped, as illustrated. The spaces between the teeth 38 are adapted to receive the cosmetic from the compartment 11 and carry it outwardly to the chamber 20. The series of teeth 38 are spaced inwardly from the opposite ends of the slide 13. When the slide 13 is in its fully in or retracted position its untoothed outer end portion completely occupies and closes the opening 75

37 to prevent the entrance of air to the compartment 11 and to prevent the leakage of the cosmetic from the compartment. In a like manner when the slide 13 is in the fully extended 5 position its untoothed inner portion fully occupies and closes the opening 37. The crests of the teeth 38 are adapted to slidably engage the wall of the opening 37. The partition 19 is of such thickness that the upper wall of the opening 37 is engageable by the crests of any two adjacent teeth 38 when the slide is in an intermediate position to prevent the entrance of air to the compartment 10 11 irrespective of the position of the slide.

The invention includes stop means for limiting 15 the travel or movement of the slide 13. A stop member 39 is secured to the inner end of the slide 13 by a screw 39^a and projects from the upper side of the slide 13. The stop member 39 is adapted to engage against the partition 19 20 to stop or limit the outward movement of the slide 13. A post 40 projects inwardly from the case end 16 and is engageable by the screw 39^a or the inner end of the slide 13 to limit the inward travel of the slide 13. The member 39 25 and the stop post 40 are adapted to stop the slide 13 in positions where its untoothed end parts occupy the opening 37 to close off the same, as described above.

Guide means is provided to hold the slide 13 30 in its proper sliding cooperation with the lower case wall 14. The upper surface of the slide 13 and the crests of the teeth 38 may slidably engage the lower ends of the plate 24 to assist in guiding and stabilizing the slide 13. A guide plate 41 35 projects inwardly from the partition 19 and lies against one case side 15. The lower edge of the plate 41 cooperates with the upper surface of the slide 13 and the crests of the teeth 38 to guide and stabilize the movable slide. The opposite side walls or sides 15 of the case 10 are 40 slidably engaged by the sides of the slide 13 and prevent undesirable lateral movement of the slide.

The means for shifting or operating the slide 13 45 comprises a stem 42 projecting axially from the outer end of the slide. The stem 42 extends outwardly to pass through an opening 43^a in the end 17. The stem 42 may be relatively small in diameter and is shaped and located to clear the brush tufts 33 when the brush 12 is in the chamber 20. A suitable knob 43 is provided on the outer end of the stem 42 and is engageable at the exterior of the case 10 to facilitate the operation of the slide. A block or stopper part 44 is 50 carried by the stem 42 and is adapted to close the opening 43^a when the slide is in its fully retracted position. The part 44 may have tapered or inwardly convergent sides and ends to wedge in the opening 43^a to fully close the same. When 55 the slide 13 is in its fully extended position with the stop 39 engaging the partition 19, the plain or untoothed outer end part of the slide closes the opening 43^a while the plain untoothed inner portion of the slide occupies or closes the opening 37. This relationship of parts is clearly illustrated in Fig. 7 of the drawing. The parts are related so that the slide teeth 38 cooperate with the inner ends of the brush tufts 33 when the brush is in its retracted position and the slide is moved outwardly from the supply compartment 11. Because of this relationship the cosmetic carried between the teeth 38 is effectively and evenly distributed on the outer portions of the brush tufts 33 when the slide is pulled outwardly. 60

75 It is believed that the operation of the device

of this invention will be readily understood from the foregoing detailed description. The compartment 11 may normally contain a supply of the mascara or cosmetic and as the slide 13 is normally in the retracted position the cosmetic 5 is contained in a substantially air tight compartment. The brush 12 is normally housed in the chamber 20 where it is protected and cannot come in contact with the hands, clothing or the like. Figs. 1, 2, 4 and 6 of the drawing illustrate 10 the device in the normal condition with the slide 13 and the brush 12 retracted.

When it is desired to use the device the knob 43 is engaged and a slide 13 is pulled outwardly to the position illustrated in Fig. 7. When the 15 slide 13 is pulled outwardly in this manner the mascara or cosmetic trapped between the teeth 38 is wiped on the outer or lower portions of the brush tufts 33. It will be apparent how the spaces between the teeth 38 carry a given amount 20 of the cosmetic and evenly distribute the same on the brush tufts 33. Following the projection or outward movement of the slide 13 the slide may be returned to its normal position. It will be observed that this operation of the slide 13 25 to apply the cosmetic to the brush 12 is carried on when the brush is entirely enclosed in the case 10 and does not necessitate the engagement of the brush or any soiled portion of the device with the hands. The inwardly convergent walls 30 of the brush chamber 20 prevent the brush tufts 33 from being drawn rearwardly or inwardly when the slide 13 is returned to its normal position. The arm 25 may then be raised or pivoted outwardly to expose the brush 12 for use. The lip 35 28 may be easily engaged to swing the arm 25 to its out position illustrated in Fig. 8. The brush 12 provided with the cosmetic as described above may then be employed to apply the cosmetic. Following the use of the brush the arm 40 25 is swung to its normal position where the brush 12 is received in the opening 20. The supply of cosmetic in the compartment 11 may be replenished from time to time by merely removing the plug 22 and injecting the cosmetic 45 through the opening 21. If the brush 12 becomes worn or frayed it may be easily replaced.

The device is easy and convenient to use and is very small and compact so that it may be carried in the purse. The mascara cannot leak from the device irrespective of the position of the slide 13 or the brush 12. The slide 13 carrying the cosmetic is at all times within the case 10 and cannot possibly soil the hands or clothing. The brush 12 is always housed in the chamber 20 when 50 not in use. 55

Having described only a typical preferred form and application of my invention I do not wish to be limited or restricted to the specific details herein set forth, but wish to reserve to myself 60 any variations or modifications that may appear to those skilled in the art or fall within the scope of the following claims.

Having described my invention, I claim:

1. A device for applying cosmetic comprising, 65 a case having a compartment for containing the cosmetic, a projectable brush carried by the case, and a toothed slide movable in the case to withdraw cosmetic from the compartment and wipe it on the brush.

2. A device for applying cosmetic comprising, 70 a case having a compartment for containing the cosmetic, a brush carried by the case for movement between a position in the case and a position at the exterior of the case, and a toothed 75

slide in the body shiftable to withdraw cosmetic from the compartment and wipe it on the brush.

3. A device for applying cosmetic comprising, a case having a compartment for containing the cosmetic and a chamber, a brush carried by the case for movement between a position in the chamber and a position where it is exposed for use, a member shiftable from the compartment to the chamber, and teeth on the member for carrying the cosmetic from the compartment to the brush.

4. A cosmetic applicator comprising, a case, a partition in the case dividing its interior into a compartment for containing the cosmetic and a brush chamber, the partition having an opening, a brush pivoted to the case to be movable between a position in the chamber and a position exposed for use, and a member movable through said opening to withdraw cosmetic from the compartment and wipe it on the brush when the brush is in the first named position.

5. A cosmetic applicator comprising, a case, a partition in the case dividing its interior into a compartment for containing the cosmetic and a brush chamber, the partition having an opening, a brush pivoted to the case to be movable between a position in the chamber and a position exposed for use, a member movable through said opening between a position in the compartment and a position in the chamber, and parts on the member for carrying cosmetic from the compartment and wiping it on the brush when the brush is in the chamber.

6. A cosmetic applicator comprising, a case, a partition in the case dividing its interior into a compartment for containing the cosmetic and a brush chamber, the partition having an opening, a brush pivoted to the case to be movable between a position in the chamber and a position exposed for use, a member movable through said opening between a position in the compartment and a position in the chamber, means for moving the member, the member occupying the opening to prevent the entrance of air to the compartment, and teeth on the member for withdrawing the cosmetic from the compartment and wiping it on the brush when the brush is in the chamber.

7. A cosmetic applicator comprising, a case, a partition in the case dividing its interior into a compartment for containing the cosmetic and a brush chamber, the partition having an opening, a brush pivoted to the case to be movable between a position in the chamber and a position exposed for use, a slide movable through said opening, a stem connected with the slide for moving the same, and teeth on the slide for drawing the cosmetic from the compartment and distributing it on the brush when the brush is in the chamber.

8. A cosmetic applicator comprising, a hollow case having a compartment for containing a supply of the cosmetic, a brush chamber, and an opening connecting the compartment and chamber, the wall of the hollow case having an opening communicating with the chamber, a brush, means pivotally supporting the brush on the case to be swung through the last mentioned opening between a position in the chamber and a position exposed for use, a slide in the case movable through the first mentioned opening to withdraw cosmetic from the compartment and wipe it on the brush when the brush is in the chamber, and an operating stem on the slide.

9. A cosmetic applicator comprising, a hollow case having a compartment for containing a

supply of the cosmetic, a brush chamber, and an opening connecting the compartment and chamber, the wall of the hollow case having an opening communicating with the chamber, a brush, means pivotally supporting the brush on the case to be swung through the last mentioned opening between a position in the chamber and a position exposed for use, a slide in the case movable through the first mentioned opening to withdraw cosmetic from the compartment and wipe it on the brush when the brush is in the chamber, and an operating stem on the slide, the walls of said chamber converging inwardly from said last mentioned opening.

10. A cosmetic applicator comprising, a hollow case having a compartment for containing a supply of the cosmetic, a brush chamber, and an opening connecting the compartment and chamber, the wall of the hollow case having an opening communicating with the chamber, a brush, means pivotally supporting the brush on the case to be swung through the last mentioned opening between a position in the chamber and a position exposed for use, a slide in the case movable through the first mentioned opening to withdraw cosmetic from the compartment and wipe it on the brush when the brush is in the chamber, and an operating stem on the slide.

11. A cosmetic applicator comprising, a hollow case having a compartment for containing a supply of the cosmetic, a brush chamber, and an opening connecting the compartment and chamber, the wall of the hollow case having an opening communicating with the chamber, a brush, means pivotally supporting the brush on the case to be swung through the last mentioned opening between a position in the chamber and a position exposed for use, a slide in the case movable through the first mentioned opening to withdraw cosmetic from the compartment and wipe it on the brush when the brush is in the chamber, means for guiding the slide, and an operating stem on the slide.

12. A cosmetic applicator comprising, a hollow case having a compartment for containing a supply of the cosmetic, a brush chamber, and an opening connecting the compartment and chamber, the wall of the hollow case having an opening communicating with the chamber, an arm pivoted on the case, a brush, means removably securing the brush to the arm to be movable between a position in the chamber and a position exposed for use, the brush being movable through the second mentioned opening, and a slide in the case movable through the first mentioned opening to withdraw cosmetic from the compartment and wipe it on the brush.

13. A device of the character described comprising, a case having a reservoir for holding a cosmetic and a chamber, a brush supported on the case for movement between a position in the chamber and a position exposed for use, and a slide movable in the case to carry cosmetic from the reservoir and wipe it on the brush when the brush is in the chamber.

14. A device of the character described including an elongated case having an elongated side opening and a filling opening at one end, a partition in the case dividing the case into two compartments, one a container compartment at said end of the case communicating with the filling opening and the other a brush compart-

- 5 ment having an elongated part beside the container compartment and at the side opening and a transverse part extending laterally from the elongated part and adjoining the inner end of the container compartment, there being an opening in the partition for passing material from the container compartment to the lateral compartment allowing material from the container compartment to be applied to brush bristles disposed in the transverse part of the brush compartment, and means for feeding material through said opening in the partition. 10

15 15. A device of the character described including an elongated case having an elongated side opening and a filling opening at one end, a partition in the case dividing the case into two compartments, one a container compartment at said end of the case communicating with the filling opening and the other a brush compartment having an elongated part beside the container compartment and at the side opening and a transverse part extending laterally from the elongated part and adjoining the inner end of the container compartment, there being an opening in the partition for passing material from the container compartment to the lateral compartment allowing material from the container compartment to be applied to brush bristles disposed in the transverse part of the brush compartment, and means for feeding material through said opening in the partition, said means including a manually operated element at the exterior of the case. 20

25 25. 16. A device of the character described including an elongated case having an elongated side opening and a filling opening at one end, a partition in the case dividing the case into two compartments, one a container compartment at said end of the case communicating with the filling opening and the other a brush compartment having an elongated part beside the container compartment and at the side opening and a transverse part extending laterally from the elongated part and adjoining the inner end of the container compartment, there being an opening in the partition for passing material from the container compartment to the lateral compartment allowing material from the container compartment to be applied to brush bristles disposed in the transverse part of the brush compartment, and means for feeding material through said opening in the partition, said means including a brush having a handle and bristles projecting laterally from the handle, the brush being normally carried entirely within the case with the handle in the longated part of the brush compartment and the bristles in the lateral compartment, and means for feeding material through said opening in the partition. 30

35 35. 17. A device of the character described including an elongated case having an elongated side opening and a filling opening at one end, a partition in the case dividing the case into two compartments, one a container compartment at said end of the case communicating with the filling opening and the other a brush compartment having an elongated part beside the container compartment and at the side opening and a transverse part extending laterally from the elongated part and adjoining the inner end of the container compartment, there being an opening in the partition for passing material from the container compartment to the lateral compartment allowing material from the container compartment to be applied to brush bristles disposed in the transverse part of the brush compartment, and means for feeding material through said opening in the partition, said means including a manually operated element at the exterior of the case. 40

45 45. 18. A device of the character described including an elongated case having an elongated side opening and a filling opening at one end, a partition in the case dividing the case into two compartments, one a container compartment at said end of the case communicating with the filling opening and the other a brush compartment having an elongated part beside the container compartment and at the side opening and a transverse part extending laterally from the elongated part and adjoining the inner end of the container compartment, there being an opening in the partition for passing material from the container compartment to the lateral compartment allowing material from the container compartment to be applied to brush bristles disposed in the transverse part of the brush compartment, and means for feeding material through said opening in the partition, said means including a material feeding element movable in the container compartment and a manually operated member for said element engageable at the exterior of the case. 50
